UNITED STATES PATENT OFFICE.

ENOCK A. CARLSON, OF DELVALLE, TEXAS.

PAPER BAG AND TWINE HOLDER.

Application filed April 21, 1926. Serial No. 103,554.

The invention provides an appliance designed chiefly for use in a grocery store, but which is adapted for general use where articles are dispensed in pokes which are made 5 secure with cord.

The invention provides a rack for the bags and a holder for the twine or cord, both being kept separate and within convenient reach, yet supported in a manner so as to be 10 out of the way.

While the drawings illustrate a preferred embodiment of the invention it is to be understood that in adapting the means to meet specific needs and requirements, the design 15 may be varied and such other changes in the minor details of construction may be resorted to within the scope of the invention as claimed, without departing from the spirit thereof.

20 For a full understanding of the invention and the merits thereof, reference is to be had to the following description and the drawings hereto attached, in which—

Figure 1 is a front view of a paper bag 25 and twine holder embodying the invention.

Figure 2 is an enlarged perspective view of a portion of the rack for receiving the paper bags, and

Figure 3 is a detail perspective view of a 30 portion of the twine holder.

Corresponding and like parts are referred to in the following description and designated in the several views of the drawings by like reference characters.

35 The appliance comprises a bar 1 which usually consists of a strip of wood of any determinate dimensions according to the size and capacity of the device. The bar 1 receives the twine or cord holder and the rack 40 for the paper bags, the same being attached thereto in any preferred way. When the bar 1 is of some considerable length it is preferred to mount a cord holder at each end thereof and since both holders are 45 constructed substantially alike a detailed description of one will suffice for a clear understanding of each.

The cord holder comprises a standard 2 having an arm 3 projected horizontally from 50 its upper end and a support 4 to receive the cord or twine 5, which is preferably in the form of a bobbin. The parts 2, 3 and 4 constitute elements of a single strip of metal bent into the form substantially as shown. 55 The cord support 4 consists of an upwardly disposed loop which is adapted to enter the

opening provided in the bobbin 5. The arm 3 overhangs the support 4 and is preferably in the plane of the bar 1 so as to economize space. A lug 6 is attached to the upper end 60 of the standard 2 adjacent the arm 3 and its upper end receives suspending means 7, whereby the device is connected to a ceiling or other convenient overhead support. A cord lifter 8 is pivoted intermediate its ends 65 to the lug 6 and the end adjacent the outer end of the arm 3 is formed with an eye 9 for the passage of the loose end of the cord 5 therethrough. The cord lifter 8 consists of a lever and the end opposite that provided with the eye 9 is of superior weight to normally hold the cord receiving end elevated.

After the bobbin of cord or twine has been placed upon the support 4 an end portion is 75 passed through openings formed in the standard 2 and arm 3, thence through the opening 9 of the cord lifter 8 and is left dangling so as to be conveniently reached when required. When the end of the cord is 80 grasped and pulled upon to unwind a length from the bobbin, the end of the lever 8 is lowered and after the required length of cord has been obtained and severed, the loose end is lifted so as to be out of the way 85

by the automatic tilting of the lever 8 which turns to elevate the end provided with the opening 9. In this manner the loose end of the cord is in position to be conveniently grasped, yet is held out of the way. The 90

rack for the paper bags comprises a plurality of loops 10 and in the preferable construction these loops are connected and form parts of a metal strap which has portions bent in the same direction to form the loops 95 10. The parts 11 of the strap intermediate the loops 10 are apertured to receive fastenings 12 such as screws, whereby the rack is attached to the bottom side of the bar 1. One member of each of the loops 10 is 100 formed with an opening 13 and the companion member has a lateral slot 14 extending through an edge thereof and projected downwardly at its inner end. A pin 15 is provided to extend across the space formed 105 between the lower ends of adjacent loops 10 and the point of the pin 15 passes through the opening 13 of one loop and its head 16 engages the slot 14 of the adjacent loop. The opening 13 is some distance above the 110 slot 14 and, in consequence, the pin 15 is inclined to the horizontal. A bunch of paper

2 bags, indicated by the dotted lines 17, is suspended from the pin 15 which is thrust through the bags adjacent the open end and when the parts are placed in position, the 5 bags assume an approximate echelon arrangement, as indicated most clearly in Figure 1, so that they may be conveniently obtained when required, each bag being stripped from a pin which tears through the 10 upper open end as the bag is pulled from the rack. It is to be understood that a pin 15 is provided for each two adjacent loops 10; it being observed that the pin, when in 15 position, extends across the space formed between the lower ends of adjacent loops. In practice it is preferred to suspend the bar 1 so that the pins 15 lie horizontally with the lower ends of the bags even and in horizontal lines.

20 Having thus described the invention, I claim:

1. A paper bag holder comprising a sup-

porting member, a connected series of U-shaped loops attached to the supporting member intermediate the loops, one member 25 of each of the loops having a slot adjacent its lower end extending inwardly and downwardly from an edge thereof and the other member having an opening adjacent its upper end, and a pin disposed between adjacent loops and having its point engaging the opening of one and its head the slot of the other.

2. A paper bag holder comprising a metal strap reversely bent to provide a series of 35 oppositely facing U-shaped loops, one member of each of the loops having a slot extending inwardly from an edge thereof and the other member having an opening, and a pin having its point inserted in an opening 40 of one loop and its head engaging the slot of the adjacent loop.

In testimony whereof I affix my signature.

ENOCH A. CARLSON. [L. S.]
